Stanley Ostrowski

BY *Dredrick Myers*

ATTORNEY

UNITED STATES PATENT OFFICE.

STANLEY OSTROWSKI, OF SCRANTON, PENNSYLVANIA.

SHADE-FIXTURE.

1,322,937.

Specification of Letters Patent. Patented Nov. 25, 1919.

Application filed April 15, 1919. Serial No. 290,201.

To all whom it may concern:

Be it known that I, STANLEY OSTROWSKI, a citizen of Poland, residing at Scranton, county of Lackawanna, and State of Pennsylvania, have invented certain new and useful Improvements in Shade-Fixtures, of which the following is a specification.

This invention relates to improvements in shade fixtures, such as are used in connection with window shades, curtains, and similar draperies.

The principal object of the invention is to provide a fixture which may be quickly and firmly applied in position to the window frame or removed therefrom at will.

A further object is to provide such fixtures with clamping or engaging devices by which the fixture may be secured without the use of screws, nails or like fastenings.

These and other like objects are attained by the novel construction and combination of parts hereinafter described, and shown in the accompanying drawings, forming a material part of this disclosure, and in which:

Figure 1 is a front plan view showing a shade fixture made in accordance with the invention.

Fig. 2 is an end elevational view of the same.

Fig. 3 is a side elevational view, and,

Fig. 4 is a fragmentary transverse sectional view taken on line 4—4 of Fig. 1.

The fixture comprises a base plate 14, having parallel side edges merging into curved ends, the plate being substantially flat upon both sides, except for a rib 15, extending marginally along one of its edges.

Formed in the upper surface of the rib 15 are a plurality of coarse ratchet-shaped teeth 16, their straight faces radiating from a post 17, fixed near the opposite edge of the plate 14, while pivoted on the bolt 17 is a lever 18, its free operative end 19 extending outwardly beyond the ratchet teeth, while a reduced neck portion 20 therebetween is beveled so that it may be engaged with any of the teeth desired.

Formed through the central portion of the lever 18 is an elongated slot 22, receptive of a pin 23 extending up from a bar 24, slideable in a longitudinal slot 25, formed in the upper surface of the plate 14. The bar 24 is bent rearwardly at 26, and formed

with a T shaped head 27, having upon its lower edge a plurality of sharp serrations 28 engageable in the wooden window frame when the lever 18 is pressed downward.

Also formed in the lower central part of the base plate 14 are a plurality of transverse recesses 30, joined by a central passage 31, receptive of a T shaped head 32, formed with the bar 33, movable in a longitudinal slot 34, in alinement with the slot 25, the bar having a rearwardly turned portion 36, merging into a T shaped head 37 provided with serrations adapted to engage with the lower side of the window frame.

It will be understood that the T shaped head 32 may be engaged in any of the recesses 30, thereby changing the relative distance between the serrations 38 and plate which, in conjunction with the serrations 28, hold the fixture firmly clamped to the window frame.

Secured upon the face of the plate 14 is a block 40 from which extends a raised transverse bar 41 upon which ordinary shade brackets 42, may be slidably engaged so that adjustment may be made in the fixtures according to the width of the curtain or shade employed.

Fixed in the plate 14, at its upper side, is a rigid wire 44, which may be outwardly turned and formed into a support for a drapery roller of the ordinary type.

From the foregoing it will be seen that a neat and effective device has been disclosed whereby shade fixtures may be removably clamped to the wooden framework of a window, and without the use of screws, nails or other fastening means.

In operation, the back of the plate 14 is placed against the frame, the T shaped head 32 engaged in an appropriate recess 30, the lever 18 being at that time in a raised position, whereupon by drawing down the lever 18, the opposing serrations 28 are caused to engage with the upper surface of the window frame, clamping the device securely thereto.

Having thus described my invention, what I claim as new and desire to secure by Letters Patent, is:

1. In a shade fixture, the combination with a rigid plate, a serrated element engageable in said plate at different distances from its center, a second serrated element slidably engaged at the upper portion of said plate,

a lever pivoted on said plate, said lever having a slot engageable with a pin in said second element, ratchet teeth formed in one of the marginal edges of said plate, means combined with said lever for engaging with said ratchet teeth, and means for supporting a shade secured to said plate.

2. In a shade fixture, the combination with a rigid plate, a rib extending marginally along one of the edges of said plate, a plurality of coarse, ratchet-shaped teeth in the upper face of said rib, a plurality of symmetrical transverse recesses formed in the face of said plate, passages leading between said recesses terminating in a slot in the lower edge of said plate, a T shaped head engageable in said transverse recesses, a bar formed with said T shaped head, said bar extending through said slot, and having a bent lower end, spur elements formed with said lower end engageable with the lower surface of the window frame, a bar slidable longitudinally in said plate at the upper portion thereof, a rearwardly turned end formed in said bar, said end having sharp spurs engageable with the upper surface of the window frame, a pin in said bar, a lever pivoted on said plate, said lever having a slot engaged with said pin, and a reduced beveled portion on said lever adapted to catch underneath of said ratchet teeth for

holding said lever when the teeth of said bar are engaged.

3. In a shade fixture, the combination with a plate adapted to be applied to a frame of a window, a rib extending marginally along one of the edges of said plate, a plurality of coarse, ratchet-shaped teeth in the upper face of said rib, a plurality of transverse recesses formed in the face of said plate, said recesses having a central passage therebetween, a bar slidable in said passage, said bar having a T shaped head engageable in any of the transverse recesses, a rearwardly turned head on said bar having sharp corrugations adapted to engage with the lower surface of the window frame, a longitudinal slot formed in the upper part of said plate, a bar slidable therein, a head formed in said bar, said head having teeth engageable with the upper surface of the window frame, a lever pivoted on said plate, pin and slot connections between said lever, and said plate, whereby the bar may be moved lengthwise, and a reduced beveled portion on said lever adapted to catch underneath of said ratchet teeth for securing said lever in an adjusted position.

In testimony whereof I have affixed my signature.

STANLEY OSTROWSKI.
